FRICTIONAL SERVOMOTOR

Stanley J. Mikina, Pittsburgh, Pa., assignor to
Westinghouse Electric Corporation, East Pittsburgh, Pa., a corporation of Pennsylvania

Application November 28, 1947, Serial No. 788,346

10 Claims. (Cl. 139—142)

1

My invention relates to frictional mechanisms which transform rotary motion into translational motion of controllable velocity, acceleration, or extent of travel for positioning, regulating and the like control purposes or for the purpose of power transmission or propulsion. Such mechanisms are disclosed in the copending patent application Serial No. 788,866, filed November 29, 1947, and also in my Patent No. 2,428,807, both assigned to the assignee of the present invention.

The main objects of my present invention are to simplify such mechanisms and to make them more rugged and more reliable.

In mechanisms of the type here dealt with, an elongated driven rotor is frictionally engaged by a friction roller which is mounted on a movable carrier to impart translational movement to the carrier when the roller axis is turned out of parallelism with the axis or generatrix of the rotor, and a control device serves to move the roller axis back to parallel position as the carriage advances along its path of travel. In the designs of the mechanism disclosed in the above-mentioned patent, the control device for turning the axis of the friction roller includes a gear rack which extends along the path of carriage travel and is engaged by a pinion journaled in the carriage. The control device of this gear type, if designed to operate with desired smoothness, is relatively intricate and is inherently limited as regards the law of dependency of the roller return adjustment upon the travel of the carriage.

It is, therefore, also an object of the present invention to eliminate geared control devices of the rack-and-pinion type, and it is further aimed at devising a control that permits more latitude as regards the law of roller return adjustment.

Still another object of the invention is to provide a frictional mechanism of the type mentioned whose driven structure is composed of a lesser number of parts and of considerably reduced weight or mass than in the mechanisms heretofore disclosed so as to permit a corresponding increase in acceleration and deceleration.

Another object of the invention is to devise such frictional mechanisms in a manner that readily permits adjusting the frictional engagement between driving rotor and friction roller with the aid of stationary adjusting means accessible from the outside and without requiring a disassembly or a removal of the friction roller carriage.

In order to achieve these objects, and in ac-

2

cordance with my invention, I provide the pivot shaft of the friction roller with a crank member which is engaged and controlled by an elongated cam member whose cam surface extends along the path of travel of the driven carriage. According to another feature of the invention, the cam member consists essentially of a slotted lever whose movement initiates the carriage travel. These and other features will be apparent from the following description of the embodiment shown in the drawing.

The illustrated servo-mechanism is designed as a drive for the fly shuttle of a weaving loom. Figure 1 shows a part-sectional view in the axial direction of the driving rotor, Fig. 2 a view taken from the right-hand side of Fig. 1, and Fig. 3 a top view relative to Fig. 1. Fig. 4 is a sectional view of carriage and friction roller, and Fig. 5 shows, partly in section, the slotted control lever and appertaining control devices of the shuttle drive.

In the drawings, numeral 1 denotes a composite stationary frame or supporting structure. A rotor 2 of elongated cylindrical shape is revolvably mounted in bearing plates 3 of the frame structure. The shaft 4 of rotor 2 is connected to an electric drive motor (not shown) operating substantially at constant speed. The rotor 2 is maintained in continuous revolution during the operating period of the weaving loom. Held against the cylindrical surface of the rotor is a friction roller 5. Roller 5 is mounted on a ball bearing 6 whose hub portion is seated on a hollow shaft 7 (Fig. 4). As shown, the roller 5 consists of the outer race member of the ball bearing which has a normal design, except that its outer surface is ground to a slight curvature to reduce the starting torque required to tilt the roller. The roller shaft 7 is attached to a fork-shaped supporting member 8. Integral with this member is a pivot shaft 9. The axis of pivot shaft 9 extends at a right angle to the geometrical axis of rotor member 2. The axis of revolution of the roller 5, i. e. the geometrical axis of hollow shaft 7, extends at a right angle to the axis of pivot shaft 9.

Shaft 9 is journaled in a thrust bearing 10. Bearing 10 rests against a carriage structure 11 equipped with four ball-bearing wheels, all denoted by 12. The wheels engage two rails 13 and 14 that are firmly attached to the frame structure 1 and extend along the rotor 2 in parallel to the rotor axis. The frame structure has a weakened or hinge-like portion, at 15 (Fig. 1), capable of permitting movement of bearing

plates 3 and rotor 2 toward the carriage structure. Two helical compression springs 16 and 17 secure the necessary frictional engagement between rotor 2 and roller 5 while forcing the carriage wheels against the rails 13 and 14. Springs 16 and 17 are disposed on threaded bolts 18 and 19 respectively. The bolts are anchored in a shuttle box structure 20 that is mounted on the frame structure to form a rigid part thereof. One end of each spring rests against a bracket 21 of the appertaining rotor bearing plate 3. The other spring end abuts against an adjusting unit seated on bolt 16 or 17. The machined hinge portion 15, as shown, is preferably located at the base of a vertical line (Fig. 1) through the point of application of the spring force on the shuttle box 20 and the point of contact of roller 5 with rotor 2.

It will be recognized that the springs 16 and 17, as compared with the biasing mechanisms disclosed in the above-mentioned patent, are not disposed on the carriage 11 so that the carriage structure can be given a greatly simplified design of considerably reduced weight or mass. As a further result, the spring force can readily be adjusted without requiring a removal or disassembly of the carriage.

Attached to the carriage structure 11 is a member 22 that carries a metal cup 23 for engaging the fly shuttle 24 to be propelled by the mechanism. The cup 23 also serves to bring the shuttle to a stop on its return from the other side of the loom. The returning shuttle is braked when it enters the shuttle box 20 by wedging itself between spring-backed friction shoes 25, 26 (Fig. 1) extending the length of the shuttle box 20. Cup 23 is filled with rawhide or other suitable resilient material to be engaged by the steel-tipped nose of the shuttle.

When the axis of revolution of friction roller 5 is in the illustrated position of parallelism with the generatrix of rotor 2, the revolution of the rotor has merely the effect of revolving the roller 5 but imparts no driving force to the carriage structure 11. When shaft 9 is turned, thereby twisting the roller axis relative to the generatrix of rotor 2, the carriage assembly is propelled along the rails at a velocity substantially equal to the peripheral velocity of the rotor times the tangent of the angle through which shaft 9 has turned. In order to impart high translational acceleration to the carriage or shuttle, for instance in the order of 100 times gravity, the angular adjustments of the shaft 9 must be accurately controlled within short intervals of time. For example, in a specific loom shuttle drive, the shuttle is uniformly brought up to a speed of 45 feet per second within about $\frac{1}{30}$ second at the end of 6 inches of travel. From this point on, the carriage begins a uniform deceleration that brings it to a stop in another 6 inches of travel, while the shuttle travels under its own momentum to the other side of the loom. The means for securing a control of this kind will be described presently.

The pivot shaft 9 carries an arm or the like crank member 27 whose actuating end is equipped with a roller 28 to engage the cam surface of a cam member 29 (Figs. 1, 4, 5). The cam member is designed as an elongated lever and extends along the rotor 2 and along the path of travel of carriage 11. The cam surface is formed by the edges of an elongated slot 30 which engages the roller 28 of the crank member 27 at all points of travel of the carriage. The slot 30 and the cam surface formed thereby may have linear

shape. Preferably, however, the slot and cam surface are given a curvature such as illustrated in Fig. 5.

The lever 29 has two pivot pins 31 and 32 located near the respective ends of the cam slot 28. Pivot pin 31 is linked to the piston assembly 33 of a hydraulic adjusting device whose cylinder 34 is firmly attached to a part 35 appertaining to the frame structure 1. A return spring 36, extending between part 35 and lever 29, tends to hold the pivot pin 31 and piston assembly 33 in the illustrated position. When hydraulic pressure is applied, the assembly and pivot are moved downward in opposition to spring 36. When the pressure is released, the pivot is returned to the illustrated normal position of rest by the biasing force of spring 36.

The pivot pin 32 is linked to the piston assembly 37 of another hydraulic adjusting device which is firmly attached to the frame structure 1 and equipped with a return spring 38. When hydraulic pressure is applied to cylinder 38, a pivot 32 is lifted in opposition to spring 39.

The hydraulic pressure is provided and controlled by a system which is designed in accordance with the principles disclosed in the copending application Serial No. 787,230, filed November 20, 1947 of L. B. Lynn and S. J. Mikina. The system includes a four-way valve, denoted as a whole by 40, and a source of pressure 41 consisting of a positive displacement pump, such as a gear pump. The pump has an inlet duct 42 which leads into the sump or low-pressure side of the pump, and communicates with two conduits 43 and 44 leading to the low-pressure sides of the respective piston assemblies 33 and 37 in the respective cylinders 34 and 38 of the two pivot adjusting devices. The outlet duct of the pump 41 is connected by two pressure conduits 45 and 46 to respective chambers 47 and 48 of valve 40. These valve chambers are in communication with the high-pressure sides within the cylinders 34 and 38 by pressure conduits 49 and 50 respectively. Two spring-biased check valves 51 and 52 establish a communication of respective valve chambers 47 and 48 with the neutral or inlet duct 42 of the pump if an excessive pressure occurs within the valve chambers. During normal operation, the check valves 51 and 52 remain closed so that these valves do not participate in the control operation proper. A double-acting valve member 53, which comprises two rigidly interconnected valve discs, is arranged in the valve chamber 47. A similar double-acting valve member 54 is located in chamber 48. Valve members 53 and 54 are rigidly interconnected by a rod 55 which carries a magnetic armature 56 movable between two electromagnets 57 and 58 and normally biased by two springs 59 and 60 to assume the illustrated centered position. The two magnets 57 and 58 are connected to a suitable current source schematically represented at 61, and are controlled by a switch 62. The switch has a movable control member 63 which is normally in the illustrated open position and can be tilted either way to energize magnet 57 or 58. Consequently, when the switch 62 is actuated, only one of the two magnets is energized at a time and, by attracting the armature 56, causes the two valve members 53 and 54 to move either to the right or to the left, depending upon which magnet is in operation.

When the pump 41 is running and the switch member 63 in the illustrated center position, the four individual valves of which the members 53

and 54 form part are all open. Consequently, a continuous flow of liquid is maintained through conduit 45, chamber 41, cavity 64, and neutral duct 42; and a second path of continuous fluid circulation exists from conduit 46 through chamber 48 and cavity 64 to duct 42. As a result, the pressure applied to the cylinders 34 and 38 is insufficient to move the piston assemblies in opposition to spring 36 or 39, and the cam lever 29 remains in the illustrated position. When under these conditions the carriage 11 is located at the left end of its path of travel with cam roller 28 at the place shown in Fig. 5, the axis of friction roller 5 is parallel to the generatrix of rotor 2. Consequently, the friction roller does not impart movement to the carriage 11.

When now the switch member 63 in Fig. 5 is moved to the left to energize the magnet 51, the armature 56 and the valve members 53 and 54 are shifted to the right. This has the effect of closing the communication between conduit 45 and chamber 47 or of increasing the flow impedance in that communication while more freely opening the chamber 47 toward the cavity 64. At the same time, the communication between pressure conduit 46 and chamber 48 becomes more freely open, while the communication between chamber 48 and cavity 64 is closed or more obstructed. The pressure from conduit 46 is now applied through chamber 48 and conduit 50 to the cylinder 38 with the effect of lifting the pivot pin 32. The pressure from conduit 45 is blocked from acting through chamber 47 and conduit 49 on the cylinder 34 so that the pivot pin 31 remains in the illustrated position of rest.

The resulting movement of the lever 29 is a rotation about the then stationary pivot pin 31. The roller 28 is lifted, relative to Fig. 5, and performs a movement which, relative to Fig. 4, extends out of the plane of illustration, for instance toward the observer. It will be recognized from Fig. 4 that such a movement of roller 28 causes the axis of roller 5 to assume an angle relative to the generatrix of rotor 2 at the point of contact between rotor 2 and roller 5. As explained above, this results in an acceleration of the carriage 11 along the rails 13 and 14, the travel being in the direction from the left to the right relative to Figs. 2, 3 and 5.

During the travel of the carriage, the roller 28 moves along the slot 30. The maximum speed of the carriage is reached when it is approximately at the center point of the available distance of travel. Beyond this point, the roller 28 is progressively turned back so that the carriage decelerates and is eventually brought to a stop near the right-hand end of lever 29 when the axis of roller 5 is again in parallel to the generatrix or axis of revolution of rotor 2.

During the second half of the carriage travel, the switch 63 is returned to the initial position so that the pivot pin 32 returns to the illustrated position of rest. Consequently, when the carriage reaches the end of its travel, the lever 29 has again the position shown in Fig. 5. When, thereafter, the switch member 63 is actuated in the opposite direction, the pivot 31 is lowered in order to cause the carriage to be accelerated in the return direction. When, thereafter, the switch member 63 is returned to the initial position, the pivot pin 31 is again lifted so that the lever 29 has the position shown in Fig. 5 when the carriage reaches the left end of its travel.

The proper actuation of the contact member 63 is effected by means of a control cam or the

like mechanism (not shown) actuated from the loom drive in proper correlation to the other operating devices of the machinery. The velocity of the carriage 11 as it travels along the guide rails 13 and 14 is determined by the angular position of the roller axis. Since this position is at all times controlled by the controllable positioning of the cam member or lever 29, the translational velocity and acceleration of the carriage is always subject to a definite control action.

In order to impart to the carriage a desired motion, for instance one which has constant acceleration up to the moment of maximum speed at which the shuttle will fly off, the angular adjustment of the pivot shaft 9 must follow the proper law as a function of time. This is done by tilting the end at which the carriage is located when it starts its movement about the pivot axis of the other cam pivot member. The rate at which the roller pivot is turned depends of course on the operating characteristics of the lever mechanism and the appertaining hydraulic control devices. These conditions may be such that the desired character of motion, for instance motion of constant acceleration, cannot readily be obtained if the cam surface or slot of the cam member is of straight shape. However, whatever the law of motion of the tilting end of the cam lever 29 may be, the curvature of the cam slot may be chosen so as to cause the carriage to move with constant or other desired acceleration. This moves any restrictions on the type of adjusting and control devices used for controlling the position of the cam lever. It thus will be clear that adjusting devices other than the hydraulic type device exemplified by the drawings can be used if desired. For instance, the cam lever may be directly actuated by control cams which form part of the loom driving machinery.

When using a hydraulic system as shown in Fig. 5, the application of a curved cam surface permits using a simple gear pump of constant speed and constant fluid displacement so that the actuated end of the control lever moves at substantially constant speed. Under these conditions, the shape of the cam curve or cam slot can be precisely calculated for the condition of constant output acceleration of the drive carriage or for any other prescribed law of motion. For obtaining constant acceleration and operating with a lever displacement of constant speed, the cam slot has substantially the curved shape shown in Fig. 5.

As mentioned above, the cam member is preferably designed so that the carriage reached maximum speed at the midpoint of its travel, and the roller pivot is then gradually brought back to its starting position. The law of return motion under the action of the spring 36 or 39, in general, will be different from the law of lever motion effected by the hydraulic control system, but the curvature of the lever slot for the second half of the carriage travel can readily be designed to bring the carriage to a stop with constant deceleration or with any law of deceleration within the range of the mechanism.

After the carriage has reached the end of its shuttle driving travel, it is returned to its starting point by pivoting the slotted lever 29 about its left-end pivot 32 and, first lowering the right-hand pivot 31 in order to accelerate the shuttle and then raising the right-end pivot 31 back to its illustrated position to decelerate the shuttle to a stop. The time for the return motion

of the carriage may be longer than that for forward motion by at least the time required by the shuttle to travel to the other side of the loom and back. Therefore, the return accelerations of the carriage may be considerably lower and it is not necessary to provide for constant acceleration on carriage return. This means that little consideration need be given to the design and operation of the return control elements. By the same token, the shape of the cam slot is less important for the return stroke so that a slot curve that is designed for constant acceleration on the forward stroke of the carriage motion will still be satisfactory for the lesser requirements of the return motion.

Since the two pivot points of the control lever should preferably lie on a line parallel to the line of carriage travel, another important advantage of the curved slot becomes apparent when one considers what would happen if a straight slot were used and if the proper law of carriage motion were attained solely by a proper shaping of the lever actuating cam or by properly varying the flow to the actuating hydraulic cylinders. For one thing, a straight control slot would have to have its axis exactly in a plane passing through the axis of the drive rotor 1. The slightest tilt from parallelism with this plane would result in a tilt of the fork 3 and cause a slow creep of the drive carriage to the end of its travel, at which point a sliding and abrasion of wheel 2 and rotor 1 would take place. Moreover, even if the slot axis were properly oriented, the unavoidable clearance between the roller and its slot, and between the roller shaft and roller would still make it possible for fork 3 to tilt slightly and creep in one direction or the other during the intervals of time when the shuttle was not being propelled.

The difficulty of unwanted creep of the carriage is completely eliminated by making the cam surface or slot curved and by making it intersect at an angle the line parallel to the drive rotor axis. For example, when the tangent to the slot axis intersects the line in question at an acute angle in a clockwise sense at each end of the slot, the carriage position of rest is definitely determined by these points of intersection. Then, any tendency for the carriage to creep off the intersection points causes the slot to turn the crank arm 14 of fork 3 in such a direction as to return the carriage to the points of intersection in question. The carriage may then be said to be self-regulated as to the stability of its stopping position at each end of its stroke.

Although the frictional servo-rotor specifically described in the foregoing and shown in the drawings is designed as a shuttle drive for weaving looms, it is apparent that the invention can likewise be embodied in mechanisms for other purposes, such as the propulsion or control of torpedoes, aircraft, gun control systems, and, in general, in servo-mechanisms for which an aperiodic or non-oscillatory response is desirable.

It should also be understood that while I have illustrated and specifically described a mechanism whose driving rotor is cylindrical, the rotor may be given conical shape or generally the shape of a body of revolution. It will be obvious to those skilled in the art upon study of this disclosure that modifications, embodiments, and applications of the invention other than those specifically mentioned are possible, in accordance with the gist and principles of my invention, and without departure from the essential features of the

invention set forth in the claims annexed hereto.

I claim as my invention:

1. A device for deriving translational motion from a source of rotary power, comprising a rotor shaped as a body of revolution with a substantially straight generatrix and revolvable about its geometric axis, a structure movable along said rotor, a pivot journalled on said structure, a roller revolvably mounted on said pivot about a roller axis extending at a right angle to that of said pivot, said roller being in frictional engagement with said rotor, a crank member on said pivot for turning the latter, a cam member having a slot engaged by said crank member and extending along the path of travel of said structure for turning said pivot during said travel.
2. A device for deriving translational motion from a source of rotary power, comprising a rotor, a structure movable along said rotor, a pivot shaft revolvably mounted on said structure, a roller in frictional engagement with said rotor and revolvably mounted on said pivot shaft so that the axis of roller revolution extends at a right angle to the axis of said pivot shaft, a crank member attached to said pivot shaft for turning said shaft in order to vary the angular position of said axis of revolution relative to the direction of the generatrix of said rotor at the point of engagement with said roller, a cam member extending along the path of travel of said structure and engaging said crank member during the travel of said structure for turning said pivot, and control means connected with said cam member for moving it to cause said crank member to turn said pivot shaft.
3. A device for deriving translational motion from a source of rotary power, comprising a rotor, a structure movable along said rotor, a pivot shaft revolvably mounted on said structure, a roller in frictional engagement with said rotor and revolvably mounted on said pivot shaft so that the axis of roller revolution extends at a right angle to the axis of said pivot shaft, a crank member attached to said pivot shaft for turning said shaft in order to vary the angular position of said axis of revolution relative to the direction of the generatrix of said rotor at the point of engagement with said roller, a movable cam member extending along the path of travel of said structure and engaging said crank member during the travel of said structure for turning said pivot, and control means connected with said cam member for moving it to cause said crank member to turn said pivot shaft.
4. A device for deriving translational motion from a source of rotary power, comprising a rotor shaped as an elongated body of revolution with a substantially straight generatrix and being revolvable about its geometric axis, a structure movable along said drive member, a pivot member mounted on said structure and being revolvable relative thereto, a friction roller revolvably mounted on said pivot member and in frictional engagement with the peripheral surface of said rotor, said pivot member having a crank member for turning said pivot member to control the angular position of the axis of revolution of said roller relative to the direction of the generatrix of said rotor member at the point of engagement with said roller so that, during revolution of said rotor, said structure is driven along said rotor when said roller axis is placed at an angle to said direction, a lever ex-

tending along said rotor and having a slot engaging said crank member, pivot means engaging said lever at one end thereof, and control means connected to said lever for moving it about said pivot means in order to control said lever to turn said pivot member.

5. A device for imparting controlled translational motion from a source of rotary power, comprising a stationary supporting frame, a rotor shaped as a body of revolution with a substantially straight generatrix and being revolvable about its geometrical axis relative to said frame, a structure guided on said frame for motion along said rotor, a pivot member revolvably mounted on said structure, a friction roller revolvably mounted on said pivot member and in frictional engagement with said rotor, said pivot member having a crank for turning said pivot member in order to control the angular position of the axis of revolution of said roller relative to the direction of the generatrix of said rotor so that, during revolution of said rotor, said structure is caused by said roller to travel along said rotor when said roller axis is placed at an angle to said direction, a lever having a cam surface extending along said rotor and slidably engaged by said crank for progressively turning said pivot member as said structure travels along said rotor, two pivoting devices linked to said lever at pivot points near the respective ends of said cam surface, and control means connected to said pivoting devices for causing either device to move said lever about the pivot point of said other device.

6. A device for imparting controlled translational motion from a source of rotary power, comprising a stationary supporting frame, an elongated rotor revolvably relative to said frame, a structure guided on said frame for motion along said rotor, a pivot member mounted on said support and being revolvably relative thereto, a friction roller mounted on said pivot member for revolution about an axis at a right angle to that of said pivot member, said roller being in frictional engagement with said rotor, said pivot member having a crank for turning the axis of revolution of said roller at an angle to the direction of the generatrix of said rotor in order to cause said structure to move along said rotor, a control lever having a cam surface extending along said rotor and engageable by said crank in all travelling positions of said structure, said lever having two pivot means disposed near the respective ends of said cam surface, two actuating devices linked to said respective pivot means and having each a spring for normally holding said lever in a given position, and control means connected with said devices for causing either device to move the appertaining pivot means in opposition to the appertaining spring about the axis of the other pivot means.

7. A shuttle drive, comprising an elongated cylindric rotor revolvable about its cylinder axis, a wheeled carriage movable along said rotor in parallel to said axis and having shuttle engaging means for imparting motion to the shuttle to be driven, a pivot member mounted on said carriage so as to be revolvably relative thereto, a friction roller revolvably mounted on said pivot member and in frictional engagement with the cylindric surface of said rotor, a crank arm forming part of said pivot member for turning it relative to said structure in order to control the angular position of the roller relative to said cylinder axis

so that, during revolution of said rotor, said structure remains at rest when said roller axis is in parallel to said cylinder axis and is caused to move along said drive member when said roller axis is placed at an angle to said cylinder axis, a movable cam member having a cam surface extending along said rotor and engaging said crank member in all travelling positions of said carriage, adjusting means connected with said cam member for moving it between limit positions, control means for controlling said adjusting means to move said cam member for starting and stopping said carriage.

8. A shuttle drive, comprising an elongated cylindric rotor revolvable about its cylinder axis, a wheeled carriage movable along said rotor in parallel to said axis and having shuttle engaging means for imparting motion to the shuttle to be driven, a pivot member mounted on said carriage so as to be revolvably relative thereto, a friction roller revolvably mounted on said pivot member and in frictional engagement with the cylindric surface of said rotor, a crank arm forming part of said pivot member for turning it relative to said structure in order to control the angular position of the roller relative to said cylinder axis so that, during revolution of said rotor, said structure remains at rest when said roller axis is in parallel to said cylinder axis and is caused to move along said drive member when said roller axis is placed at an angle to said cylinder axis, a movable cam member having a cam surface extending along said rotor and engaging said crank member in all travelling positions of said carriage, said cam member being movable from an intermediate position to two limit positions and having two pivot means spaced from each other, two adjusting devices engaging said respective pivot means, spring means for biasing said adjusting devices to normally hold said cam member in said intermediate position, and control means connected with said devices for alternately controlling them so that either device, when operative, moves said cam member about the pivot means engaged by the other device.

9. A shuttle drive, comprising an elongated cylindric rotor revolvable about its cylinder axis, a wheeled carriage movable along said rotor in parallel to said axis and having shuttle engaging means for imparting motion to the shuttle to be driven, a pivot member mounted on said carriage so as to be revolvably relative thereto, a friction roller revolvably mounted on said pivot member and in frictional engagement with the cylindric surface of said rotor, a crank arm forming part of said pivot member for turning it relative to said structure in order to control the angular position of the roller relative to said cylinder axis so that, during revolution of said rotor, said structure remains at rest when said roller axis is in parallel to said cylinder axis and is caused to move along said drive member when said roller axis is placed at an angle to said cylinder axis, a movable cam member having a cam surface extending along said rotor and engaging said crank member in all travelling positions of said carriage, said cam surface being curved in accordance with a desired control performance, and control means connected with said cam member for moving it in order to turn said pivot member in a position to start movement of said carriage whereupon said pivot member during said movement is gradually returned to carriage-stopping position in accordance with the performance determined by the curvature of said surface.

10. A shuttle drive, comprising an elongated cylindric rotor revolvable about its cylinder axis, a wheeled carriage movable along said rotor in parallel to said axis and having shuttle engaging means for imparting motion to the shuttle to be driven, a pivot member mounted on said carriage so as to be revolvable relative thereto, a friction roller revolvably mounted on said pivot member and in frictional engagement with the cylindric surface of said rotor, a crank arm forming part of said pivot member for turning it relative to said structure in order to control the angular position of the roller relative to said cylinder axis so that, during revolution of said rotor, said structure remains at rest when said roller axis is in parallel to said cylinder axis and is caused to move along said drive member when said roller axis is placed at an angle to said cylinder axis, an elongated lever having a slot extending along said rotor and engaged by said crank, said lever having two pivot means near the respective ends of said slot, two hydraulic adjusting devices en-

gaging said respective pivot means and having spring means for biasing said pivot means toward given positions respectively, and valve means for alternately actuating said adjusting means to move the respective pivot means away from said normal position in order to turn said pivot member in a position to start movement of said carriage whereupon said pivot member during said movement is gradually returned to carriage-stopping position as said crank moves along said slot.

STANLEY J. MIKINA.
